UNITED STATES PATENT OFFICE.

CLARK B. FELL, OF NORTHFIELD, OHIO.

GRADING-MACHINE.

1,150,588.

Specification of Letters Patent. Patented Aug. 17, 1915.

Application filed February 7, 1914. Serial No. 817,268.

To all whom it may concern:

Be it known that I, CLARK B. FELL, a citizen of the United States, resident of Northfield, county of Cuyahoga, and State of Ohio, have invented a new and useful Improvement in Grading-Machines, of which the following is a specification, the principle of the invention being herein explained and the best mode in which I have contemplated applying that principle, so as to distinguish it from other inventions.

My invention relates to grading machines, its object being to provide a grading machine which may be economically manufactured and which will be efficient in its use.

Specific objects of the invention are to provide a grading machine which may be used in grading soil of all characters, which may be readily turned around, and which will require a minimum power for its operation.

The said invention consists of means hereinafter fully described and particularly set forth in the claims.

The annexed drawings and the following description set forth in detail certain means embodying my invention, the disclosed means, however, constituting but one of various mechanical forms in which the principle of the invention may be employed.

In said annexed drawings:—Figure 1 represents a plan of a grading machine embodying my invention. Fig. 2 represents a vertical transverse section taken upon the planes indicated by lines II—II in Fig. 1. Fig. 3 represents a side elevation of the machine. Fig. 4 represents, upon an enlarged scale, a fragmentary side elevation with parts broken away, illustrating the means for raising and lowering the frame. Fig. 5 represents a vertical transverse section, partly in elevation, taken upon the planes indicated by lines V—V in Fig. 4. Fig. 6 represents a detail vertical section of the bearing-block and crank-arm together with the upper end of the supporting rod used for raising and lowering the plow-arm.

The illustrated embodiment of my invention comprises a main frame 1 of general rectangular form, on the left side of which, as viewed in Fig. 2, and extending upwardly and transversely, is suitably mounted an elevator or conveyer 2. This elevator consists of the usual belt 3, made of canvas or other suitable material, the said belt running around suitable rollers 4, 4, in the usual

manner. These rollers are connected by suitable means (not shown) with a supporting and driving wheel 5 suitably mounted upon the frame and beneath the elevator, as 60 shown in Fig. 2. The elevator and means for operating same form no part of my present invention and it is therefore deemed unnecessary to describe same in detail, since the manner of mounting and operating such an elevator is well-known to those skilled in the art. 65

Secured on the right-hand inside of the front member 6 of the main frame, is a supporting casting 7 provided with lugs 8, 8, 70 between which is supported the front end of an oscillatory plow-arm 9, the said end being suitably secured by means of a pin 10, Fig. 1. This arm extends backwardly and at an angle toward the elevator, as shown, 75 and upon its free end is mounted a plow-disk 11 which rotates freely. Suitably secured to the plow-arm 9 is a scraper 12 for scraping the soil from the interior of the plow-disk. This scraper and the details of 80 construction thereof form no part of my present invention and need not therefore be described further herein.

Having its lower end articulating with the plow-arm 9 is an upwardly extending rod 85 13. The upper end of this rod extends through an oscillatory bearing-block 14, Fig. 6, a suitable bore 15 being provided through which the rod slides, said rod being provided with a cap 16 which prevents it from 90 passing completely therethrough. This bearing-block is provided with trunnions 17, 17, which are mounted in bearings 18 formed in the end of a bifurcated crank-arm 19. Intermediately of the bearing-block 14 and 95 plow-arm 9 and surrounding the rod 13 is a coil-spring 20.

It will be seen from the above described arrangement of parts, that the plow-arm 9 may be caused to yield upwardly when the 100 plow-disk meets any hard obstruction such as a stone, the spring 20 returning the arm and disk to its normal position when such obstruction is passed.

The crank-arm 19 is secured to a longitudinally extending shaft 21 mounted upon the upper portion of an upwardly and longitudinally therefor extending auxiliary frame 22, the latter being suitably secured to the main frame 1. To the front end of 110 this shaft is secured a gear-segment 23 whose teeth mesh with a worm 24 secured to a

transversely extending shaft 25 to which is secured a suitable hand-wheel 26. It will therefore be seen that by rotating the hand-wheel 26, the shaft 21 may be oscillated so as to raise or lower the plow-arm 9 and the plow-disk attached thereto.

Having its upper end mounted in a bearing 27, Fig. 5, secured to the front portion of the side member 28 of the frame, is a 10 downwardly extending axle-bar 29. The lower end 30 of this axle-bar forms a journal for a side supporting wheel 31. The upper end of this bar is secured in the bearing 27 by means of a collar 32 which 15 itself is secured in place by means of set screw 33.

Mounted upon the side member 28 is a ratchet-segment 34, Fig. 4, and pivotally mounted upon the said frame member 28 is 20 an adjusting-lever 35 upon which is suitably mounted a pawl 36 adapted to engage the teeth 37 of the segment 34, said pawl being held in normal engagement therewith by means of a suitable coil-spring 38, as will 25 be understood. Having its upper end articulating with the adjusting-lever 35 is a bar 39 whose lower end articulates with a strap 40 secured to the axle-bar 29 and near the lower end thereof. This axle-bar normally 30 extends in an angular direction toward the rear, as shown in Fig. 4. A suitable rod 41 and grip 42 are provided for actuating the pawl 36 in the usual manner. It will therefore be seen from the above described construction that the axle-bar 29 may be oscillated in its upper bearing 27 and the frame 35 1 therefore raised or lowered with reference to the axis of the wheel 31.

Rigidly secured to the front of the main 40 frame 1 and at about the middle of the transverse member 6 is a forwardly extending auxiliary frame 43 upon the forward end of which is pivotally mounted, by means of the king bolt 44, a front truck 45 provided with suitable wheels 46. This truck is 45 provided with the usual tongue 47 and auxiliary parts whereby the device may be drawn by horses as will be readily understood.

50 In operating the above described device, the hand-wheel 26 is turned so as to impart to the plow-arm and plow-disk the required position. The adjusting-lever 35 is then operated to lower the frame to the required 55 position, the weight of the frame and parts connected therewith, causing the plow-disk to project into the soil. The machine then being drawn forwardly, the plow-disk 11 throws the earth upwardly and laterally to 60 the left upon the traveling belt or elevator 2, the soil being thus discharged laterally of the entire machine on the left thereof, from whence it may be discharged into a wagon or directly to the ground in the 65 usual manner.

By arranging the wheel 5 under the elevator, the additional supporting wheel 31 at the side and the front truck in front and near the center, it will be seen that the entire machine may be turned around within 70 a comparatively small area and it is therefore relatively easy of manipulation in this respect.

It will also be seen that by the arrangement of parts whereby the main frame may 75 be raised or lowered with reference to the side wheel 21 and the arrangement whereby the plow-arm may be raised and lowered, a proper adjustment of the plow-disk is readily obtained. Furthermore, as previously 80 mentioned, when the plow-disk meets with any hard obstruction such as a stone, the arm 9 will yield upwardly and permit 85 said disk to pass such obstruction, after which the spring returns same to its normal operating position.

Having fully described my invention, what I claim and desire to secure by Letters Patent is:—

1. In a grading machine, the combination 90 of a main frame; a supporting wheel mounted oscillatorily on said main frame; means for raising and lowering said frame with reference to said wheel; an elevator mounted upon said frame and extending transversely thereof; a supporting wheel mounted beneath said elevator; a plow-arm having one end pivotally connected with the front portion of said frame; a plow-disk mounted upon the front end of said plow-arm; means 95 for raising and lowering said plow-arm; and a wheel truck and wheels mounted thereon pivotally connected with the front portion 100 of said frame.

2. In a grading machine, the combination 105 of a main-frame; a single supporting wheel mounted upon one side and forwardly of the middle of said frame; an elevator mounted upon the latter and extending laterally and upwardly therefrom on the side opposite 110 that upon which said wheel is mounted; a second supporting-wheel mounted upon said frame and upon such opposite side; a pivotally and yieldingly mounted plow-disk mounted upon said frame intermediately of 115 said elevator and said first-mentioned side of the frame; an auxiliary frame extending forwardly of the main-frame; and a wheel-truck and wheels therefor pivotally mounted 120 upon said auxiliary frame.

3. In a grading machine, the combination 125 of a main rectangular frame having its major dimension extending transversely; a single supporting-wheel mounted upon one side of said frame and near the front thereof; an elevator mounted upon the latter and extending laterally and upwardly therefrom on the side opposite that upon which said wheel is mounted; a second supporting-wheel mounted upon said frame and upon 130

such opposite side and beneath said elevator; a pivotally and yieldingly mounted plow-disk mounted upon said frame intermediately of said elevator and said first-
5 and lowering said disk; a second auxiliary longitudinally and upwardly extending frame secured to said main frame; means mounted on said auxiliary frame for raising and lowering said disk; a second auxiliary
10 frame secured to the front and extending

forwardly of the main frame; and a wheel-truck and wheels therefor pivotally mounted upon said second auxiliary frame.

Signed by me, this 22nd day of January, 1914.

CLARK B. FELL.
